(57) **CLAIM**

The ornamental design for master control unit for controlling shades and lights, as shown and described.

DESCRIPTION

FIG. 1 is a perspective view of a master control unit for controlling shades and lights of a first embodiment in accordance with the present invention;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof;

FIG. 7 is a bottom view thereof;

FIG. 8 is a perspective view of a second embodiment of FIG. 1; and,

FIG. 9 is a front elevation view thereof, wherein the rear view, left side view, right side view, top view, and bottom view correspond respectively to FIGS. 3, 4, 5, 6, and 7.
